UNITED STATES PATENT OFFICE

2,451,813

ELECTRON DISCHARGE DEVICE HAVING AN ELECTRON BEAM PASSAGE AND ALIGNING MEANS THEREWITH FOR THE CATHODE

Paul M. Dickerson, East Orange, N. J., assignor to Westinghouse Electric Corporation, East Pittsburgh, Pa., a corporation of Pennsylvania

Application March 30, 1943, Serial No. 481,069

6 Claims. (Cl. 250—27.5)

1

This invention relates to electron discharge devices and particularly to that character of apparatus utilizing a beam of electrons.

In a beam-type of electron discharge device, one of the pre-requisites to efficiency thereof, is that the cathode be accurately aligned. Such devices of the general character illustrated in the accompanying drawing as heretofore manufactured and as shown in copending application, Serial No. 478,560, of March 9, 1943, and assigned to the same assignee as this application, required a considerable time to obtain the correct alignment during the fabricating process, amounting to approximately fifteen minutes each on an average. Not only was this very considerable time delay involved, but the aligning process introduced strains in the glass mounting which resulted in defective sealing and thus produced an objectionable amount of shrinkage in manufacture. In general aspects of the invention, therefore, an object is to overcome the deficiencies heretofore encountered in manufacture of electron discharge devices of the beam type.

From a more specific standpoint, an object of the invention is to provide a structure wherein the cathode is automatically aligned as a necessary product of the assembly thereof in the device.

Another object of the invention is to assure proper alignment of the cathode by the dimensions and interfitting of the parts controlling such alignment.

A further object of the invention is to improve focusing of cathodes in devices as characterized and increase efficiency of the device as a whole.

Yet other objects of the invention are to obtain rigidity of construction; to avoid vibration; to assure presence of adequate and uniform dielectric; to reduce handling of the parts and time consumed in assembly; and to obtain other advantages and results which will appear as the description progresses, both by direct recitation thereof and by implication from the context.

Referring to the accompanying drawing, in which like numerals of reference indicate the same parts throughout, an exemplification of the invention has been arbitrarily selected for the present disclosure.

Figure 1 is a view largely in longitudinal section, showing an electron discharge device of

2

the beam type with my invention incorporated in association with the cathode; and

Figure 2 is a perspective view of the dielectric collar and associated part of the focusing sleeve.

5 In the specific embodiment of the invention illustrated in said drawing, the reference numeral 10 designates an electron discharge device in general of the beam type, and shown as constructed as a body of revolution about an axis. The usual structural features of such a device comprise a cathode 11 in a plane normal to the axis at a distance from which is disposed a reflector 12 also normal to the axis, said axis passing through the centers of both the cathode and reflector. In the region intervening between the cathode and reflector is a hollow resonant chamber 13 the opposite walls of which around the axis are perforate for passing the electron beam therethrough from the cathode to the reflector and back again into the resonator. The perforate parts of the walls, for want of better term, have been identified in the art as grids, and accordingly in the order of nearness to the cathode will be here identified as the near grid 14 and far grid 15 of the resonator. Between the cathode and said near grid of the resonator is a focusing grid 16, it preferably being situated as close as electrically and mechanically feasible to the cathode. Appropriate potentials, in accordance with prior art practice are applied to the cathode, focusing grid, resonant body and reflector. The beam of electrons in its forward path will be bunched by passing through the constricted space between the near and far resonant chamber grids, and thus on the return passage through that space will be in concentrated bunches, and there giving up a large part of their energy to the resonant chamber. The resultant energy is carried off for useful purpose through an output 35 from the resonant chamber, said output being here shown as a loop and concentric line 17. One wall 18 of the resonant chamber is made flexible for tuning the resonator by an adjustment of the spaced relation of the resonant chamber grids. The outer shell is sealed and accordingly constitutes an envelope and the interior of the envelope is evacuated.

Heretofore it has been the practice to situate the cathode in a cathode chamber and align it to the best of the operator's ability both cen-

trally with respect to the axis and perpendicular to the axis. According to the present invention, I eliminate this uncertainty of alignment and incorporate means affording positive alignment. The specific construction selected for illustration of this feature of the invention will now be described.

A ceramic or other insulator 19 is provided having a bottom disc-like portion 20 forwardly from which projects a cylindrical body or shoulder portion 21 from which in turn projects a cylindrical neck 22, said bottom portion, shoulder and neck all being coaxial and successively of smaller diameter. Over the neck 22, is applied an inverted metallic cup the side wall of which is considerably longer than the neck with its margin in fitting engagement with the peripheral wall of the neck, and its edge in engagement with the forward face of the body or shoulder portion 21. The forward end face of this metallic cup is in a plane normal to the axis and constitutes afore-mentioned cathode 11, being appropriately coated or otherwise rendered electron emissive. Within the cup is a suitable heater 23 having lead-in wires 24 extending through the ceramic. It may also be here noted that a lead-in wire 25, also extending through the ceramic, constitutes a lead-in wire to the cathode for applying the desired potential thereto. Around the shoulder portion 21 in peripheral surface contact therewith, is a metallic focusing collar 26. This collar has the same difference in diameter from the diameter of the cathode cup as the difference in diameters between the shoulder and neck portions of the ceramic. The metallic focusing collar 26 is, however, considerably longer than the cathode cup and extends both forwardly and rearwardly with respect thereto. Forwardly of the body or shoulder portion of the ceramic, the focusing collar is concentric with and spaced from the cathode cup in precise parallelism in consequence of the rigid mounting of each upon the ceramic. It is a simple manufacturing operation, by utilization of an appropriate jig, to position and weld or otherwise attach the focusing grid in position perpendicular to the axis of and within the focusing collar. Resultant upon the construction shown and method outlined, the assembly enables the focusing grid and emitting face of the cathode to be close, without touching, and in exact parallelism.

At the outside of and next the forward margin of the focusing collar, is provided an insulating ferrule 28 in fitting peripheral surface engagement. The ferrule is furthermore preferably extended beyond the end of the collar and provided with an internal shoulder 29 to engage over the end of the focusing collar. The inside diameter of this shoulder and of the collar are preferably the same so as to provide a smooth inner passageway. The other end of the ferrule, that is, the near end to the cathode, has an external peripheral flange 30. The exterior peripheral face of the ferrule and the forward face of the flange seat snugly with respect to a correspondingly shaped housing member 31 forming part of the envelope between the cathode chamber and resonator chamber. The long bearing engagement of the annular wall of the ferrule with the housing member and with the focusing collar assures utmost precision in the assembled structure in addition to desired rigidity and non-vibrating mounting of the collar, ceramic insulator and cathode. The presence of the ferrule be-

tween the housing member and the focusing collar assures adequate and definite dielectric always separating those parts and furthermore enables the cathode to have a location within the housing member at desired distance from the near grid of the resonator.

I claim:

1. An electron discharge device comprising a housing formed as a body of revolution about an axis, an insulator coaxial with said housing, said insulator having an end thereof formed as a disc, having an opposite end formed as a neck, and having an intervening shoulder portion, said disc part of the insulator constituting a means 15 mounting the insulator in the said device, a focusing collar mounted on and held coaxial with said shoulder portion, and a cathode mounted on and held coaxial with the neck portion of the insulator, said collar being extended beyond the 20 cathode and braced from the said housing at the part of said collar remote from the said disc and shoulder portions of the insulator.

2. An electron discharge device comprising an envelope an intermediate part whereof comprises 25 a housing having a constricted passage for electrons, a cathode having its emitted surface cross-wise of and coaxial with said passage substantially at one end thereof, another electrode in said envelope coaxial with and opposite the other 30 end of said passage, and a collar within said envelope and having one end portion projecting from said housing coaxially of said cathode and said projecting end portion supporting said cathode, said collar having its other end portion 35 within and supported by said housing.

3. An electron discharge device comprising a housing having a passage for flow of a beam of electrons therethrough, a cathode in said passage directed toward a far end thereof, another electrode 40 opposite the far end of said passage for reception of the beam of electrons, a focusing collar around the cathode, an insulator in one end portion of said collar in engagement with both the cathode and collar bracing the cathode from 45 said collar coaxially, and means interposed between the other end portion of said collar and housing centering and aligning the collar and cathode.

4. In an electron discharge device, a housing 50 having a cylindrical passage for flow of a beam of electrons therethrough, an insulating ferrule within said housing, a focusing collar having one end portion within said ferrule and its other end portion projecting from said ferrule, and a cathode 55 within said other and projecting end portion of and aligned by said focusing collar with respect to the ferrule and housing passage.

5. An electron discharge device of the beam type having a cathode and another electrode 60 opposed to each other in an axial direction, a focusing collar in part surrounding the cathode, an insulator in engagement with and supporting both one end of said collar and said cathode and maintaining rigid axial alignment of the cathode 65 in said collar, and means at and rigidly supporting the other end of said collar and maintaining rigid alignment of the collar and cathode with the said electrode.

6. An electron discharge device of the beam type having a cathode and another electrode 70 opposed to each other in an axial direction, a focusing collar in part surrounding the cathode coaxial therewith, means supporting both one end of said collar and said cathode and maintaining rigid coaxial alignment of the cathode 75

in said collar, a grid within and crosswise of said collar and having close spacing to the cathode, and means at and rigidly supporting the other end of said collar and maintaining alignment of the collar and cathode with said electrode.
